US00D824227S

(12) **United States Design Patent** (10) **Patent No.:** **US D824,227 S**
Stender (45) **Date of Patent:** **** Jul. 31, 2018**

(54) **STAKE**

(71) Applicant: **3 T Assets, LLC**, Portage, MI (US)

(72) Inventor: **Timothy P. Stender**, Portage, MI (US)

(73) Assignee: **3 T Assets, LLC**, Portage, MI (US)

(**) Term: **15 Years**

(21) Appl. No.: **29/562,114**

(22) Filed: **Apr. 22, 2016**

(51) LOC (11) Cl. **08-01**

(52) U.S. Cl. **D8/1**

DESCRIPTION

FIG. 1 is a front perspective view of a stake, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines represent portions of the stake and form no part of the claimed design.
